S. GORLOV.
ELECTRICAL WATER HEATING DEVICE.
APPLICATION FILED FEB. 27, 1922.

Patented Nov. 21, 1922.

Inventor

Svend Gorlov

W. H. Tracy

Attorney

UNITED STATES PATENT OFFICE.

SVEND GORLOV, OF MIAMI, FLORIDA, ASSIGNOR OF ONE-TENTH TO J. H. SWINK AND C. C. SMALL, BOTH OF DADE COUNTY, FLORIDA, PARTNERS DOING BUSINESS AS SWINK & SMALL.

ELECTRICAL WATER-HEATING DEVICE.

Application filed February 27, 1922. Serial No. 539,528.

To all whom it may concern:

Be it known that I, SVEND GORLOV, residing at Miami, in the county of Dade and State of Florida, a subject of the King of Denmark, have invented certain new and useful Improvements in Electrical Water-Heating Devices, of which the following is a specification, reference being had to the accompanying drawings, forming a part 10 thereof.

My invention relates to electric heating devices for heating water or other liquids and has for its object to provide a device for this purpose which will be simple and 15 inexpensive in construction and will be particularly adapted to utilize an alternating current to heat a stream of water as it flows through pipes.

A further object of the invention is to provide a device of this character in which the 20 full energy of the current will be utilized for heating purposes.

A further object of the invention is to provide a device for this purpose which can 25 readily be connected in the usual household water supply system.

With the above indicated objects and other objects hereinafter explained in view, my invention consists in the construction and 30 combination of elements hereinafter described and claimed:

Referring to the drawings:

Figure 1 is a central vertical sectional view of an electric heating device embodying my invention taken on a plane at right angles to the planes of the heating plates.

Figure 2 is a similar view taken on central plane parallel with the heating plates and

Figure 3 is a horizontal sectional view on lines 3—3 of Figures 1 and 2.

In the drawings 1 indicates a receptacle of conducting material here shown as a section of iron or steel pipe having at its upper end a cap 2 screw threaded to the end of the receptacle and having a central screw threaded opening 3 adapted to receive a suitable delivery pipe (not shown). The lower end of the receptacle is screw threaded into the end of a collar 5 having on one side a screw threaded nipple 6 to receive an inlet pipe. Into the lower end of the collar 5 is screwed a plug 7. To the plug 7 is screwed a guard box 8 extending below the plug and

having in its base an opening 9 into which 55 is inserted a ring 10 of insulating material.

The plug 7 is provided with oppositely arranged openings in which are screwed plugs 11 and 12 of insulating material 60 through which extend screws 13 and 14 respectively. On these screws are secured horizontally extending lower ends 15 and 16 of metallic plates 17 and 18 which extend upward nearly to the upper end of receptacle 1, the upper ends of these plates being held at a suitable distance apart and away from the walls of the receptacle by a disc 20 of insulating material having openings in it for the plates and also having in 70 it openings 21 and 22 for passage of water.

The horizontally extending ends 15 and 16 rest on metallic washers 23 and 24 respectively on the upper ends of the plugs 11 and 12 and are held against these washers 75 by the heads of the screws 13 and 14. The heads of these screws are drawn downward to firmly clamp the ends 15 and 16 against the washers 23 and 24 by nuts 25 and 26 bearing against washers 27 and 28 which 80 in turn bear against discs 29 and 30 of insulating material.

The ends of wires 31 and 32 lead from a source of alternating current here indicated diagrammatically as an alternate current 85 generator.

In operation the cold water pipe of a usual water supply system is connected with nipple 6 of the collar 5 and the end of the delivery pipe is screwed into opening 3 in 90 the cap 2. The wires 31 and 32 being in circuit with the source of alternating current, and the water being turned on, the electrical impulses pass to the plates 17 and 18 and, through the water, from one plate 95 to the other and, as the walls of the receptacle are of conducting material in circuit with ground through the pipes of the water supply, also pass through the water to the receptacle. Current leakage is thus utilized 100 to aid in heating the water by its passage through it.

In the construction shown the receptacle, its cap, the collar 5, and the plug 7, are all formed of stock pipe fittings so that the device is inexpensive to construct. The plates 17 and 18 are simple in construction and the insulating plugs 11 and 12 and the screws

13 and 14 and the insulating ring 10 are all stock parts.

The rapidity of heating will, of course, depend upon the amperage of the current used.

5 With the usual city current water will be heated to near the boiling point with sufficient rapidity to permit of delivery in considerable stream. If the delivery is stopped for any considerable time the water will be 10 heated above the boiling point and steam generated.

Having thus described my invention, what I claim is:—

1. In an electrical water heating device 15 the combination of a receptacle of conducting material adapted to contain liquid to be heated provided with means for connecting an inlet and delivery pipe thereto, insulated plates of conducting material with- 20 in the receptacle spaced apart and away from the walls of the receptacle and a source of alternating current connected with the plates, the inlet and outlet pipes being connected to ground.
- 25 2. In an electrical water heating device, the combination of a cylindrical receptacle of conducting material provided at one end with a cap having an opening for a delivery pipe, and provided at the other end with a

collar having a nipple to receive an inlet 30 pipe, a plug carried by the collar provided with insulating material adapted to support plates of conducting material, said plates of insulating material extending into the receptacle at a fixed distance from each 35 other and from the walls of the receptacle, and means for connecting the plates with a source of alternating current.

3. In an electrical water heating device, the combination of a cylindrical receptacle 40 of conducting material provided at one end with a cap having an opening for a delivery pipe, and provided at the other end with a collar having a nipple to receive an inlet 45 pipe, a plug carried by the collar provided with insulating material adapted to support plates of conducting material, said plates of insulating material extending into the receptacle at a fixed distance from each other and from the walls of the receptacle, 50 means for connecting the plates with a source of alternating current, an inlet and a delivery pipe forming part of a grounded water supply system.

In testimony whereof I hereunto affix my 55 signature.

SVEND GORLOV.
